WATER TUBE STEAM GENERATOR

Gus L. Colbie, Brooklyn, N. Y., assignor to Hudson Electrical Heating Corporation, New York, N. Y., a corporation of New York

Application September 15, 1931
Serial No. 562,931

14 Claims. (Cl. 219—38)

My invention relates to a novel form of electrically heated steam generator and more particularly to an internally heated water tube, the heating member being centrally disposed within 5 the water tube.

More particularly the invention is designed to produce a multiple unit construction of a standardized steam generator in which any desired number of units may be connected together to 10 form a steam generator of any desired capacity and of the proper external contour to fit into any particular space. This last feature is particularly important in the heating of trains which are drawn out of and into terminal stations by 15 electrical locomotives, but which are heated by steam driven locomotives during the rest of each run. There are now in use, oil fired steam generators on electric locomotives, but due to the 20 limited space for this purpose, it has been difficult to arrange them in a practical way. With 25 my multiple unit arrangement, the units may be distributed about the cab in differently arranged assemblies and all connected together to operate as one unitary system. It is also adapted for 30 use in commercial boiler rooms, where the modern tendency is to arrange such boiler rooms to provide clean, comfortable surroundings for the attendant, eliminating the coal stokers, and requiring only the attention of an engineer who 35 will control the entire operation from a switch board.

This type of steam generator might be termed 35 a cellular unit structure in which each cell comprises a water tube having an electrical heating element within it capable of producing a predetermined quantity of heat and a predetermined volume of steam. Thus, each cell or unit is an 40 independent steam generator which can function as such, by reason of the particular assembly or the vertical relation of each of said units.

The vertical relation of each cell in the cellular structure is quite important to permit the operation of any desired one or group of cells, which 45 would not be possible in tubes arranged otherwise, since each tube in a vertical position always has one definite quantity of water within it which is changed to steam, each tube generating the same amount of steam, thus permitting the 50 elimination of any number of tubes from operation without affecting the others.

With this assembly, it is also possible to control 55 the generation of steam by means of electrical switches, thermostats or the like, in such manner as to generate any desired quantity, from the full capacity of all the units down to the capacity of

one single unit thus providing any desired quantity of steam when it is required.

A steam generator of this character is highly desirable for use where requirements for steam vary over certain periods each day, for instance, 60 if used in a commercial plant, the requirement may be for full capacity in the morning, half the capacity in the afternoon and perhaps a small fractional part of the capacity to provide heat for the building at night, or there may be 65 occasions such as the noon hour period when the entire steam plant operation could be suspended. The latter is an example of extreme operating conditions which can be effectively approached with the type of steam generator herein disclosed. 70

When used in a locomotive all of the cells would be used for a full train of ten cars for instance and a proportionate number of cells for 75 any number of cars less than ten.

Steam may be generated in a single cell, groups of cells or from the entire cellular assembly. Each cell or group of cells may operate independently, yet they are so correlated that all of the cells can operate in unison, each cell cooperating 80 one with another.

Thus it may be stated that with my arrangement I provide an efficient and practical type of electrically heated steam generator having 85 three points of distinction which differ from commercial boilers of any type, namely, flexibility of form, flexibility of control and flexibility of function.

Other known types of electrically heated steam generators may function in part under conditions similar to those mentioned above but could not operate as effectively and efficiently as the structure of my invention. So far as is known, no attempts have been made to develop a cellular unit structure having an electrical heating element within each cell, with an assembly such as shown and disclosed in the drawings and specifications. 90

Other features of construction include interchangeable standardized electrical heating elements and water tight envelopes surrounding same which are supported at their upper ends in the steam headers, leaving the lower ends free to expand longitudinally, but guided laterally. 100

By my invention I provide a novel arrangement of an electrically heated water tube boiler which comprises a plurality of one or more water tubes, each one of which is a separate steam generator. Water supply and steam headers are 110

provided at the tube ends, each header having branch water inlet and steam outlet connections which are joined with manifolds surrounding the headers.

5 The heat is supplied by means of a novel form of electrical resistance unit which is arranged within an envelope, said envelope being inserted within the water tube, their relative diameters being such as to leave a narrow annular water 10 passage between the shell and the tube. Said envelope is supported at its upper end leaving the lower portion free to expand longitudinally when heated. Resistance wire, of a very heavy cross section, is supported by spaced discs of 15 refractory material, said discs being mounted between ribs or shoulders formed on a casing surrounding same.

Any conventional type of feed water regulator and pump may be used as a means for maintaining a constant water level within the generator 20 tubes.

The best form of apparatus at present known to me embodying my invention is illustrated in the accompanying four sheets of drawings in 25 which

Fig. 1 is an end elevation of one form of my invention with parts broken away.

Fig. 2 is a side elevation of the structure shown in Fig. 1.

30 Fig. 3 is a plan view of the structure shown in Fig. 1, also showing a wiring diagram.

Fig. 4 is an enlarged vertical section taken on the lines 4—4 of Fig. 3.

35 Fig. 5 is a vertical section taken on the lines 5—5 of Fig. 4.

Fig. 6 is a cross section taken on the lines 6—6 of Fig. 4, and

Fig. 7 is a cross section taken on the lines 7—7 of Fig. 4.

40 Throughout the drawings like reference characters indicate like parts. In the preferred embodiment here shown the generator 10 comprises a plurality of tubular members or water jackets 12 preferably arranged vertically and joined at 45 their upper ends 14 to a series of steam headers 16, and at their lower ends 18 to a corresponding series of water headers 20. To retain the tubes 12 within the headers, I roll the ends and force same into annular recesses 13 in the header 50 openings 15 to form water and steam-tight joints, see Figs. 4 and 5. The rolling operation is performed by means of a tool which is adapted to be inserted through the upper and lower header openings, the upper openings being closed by the 55 heating unit mounting member to be described hereafter and the lower openings being closed by caps 17 which are inserted through the water inlet opening 19, in the header 20, as best shown in Figs. 4 and 5.

60 Within each water jacket 12 is suspended a centrally disposed standardized heating unit generally indicated as 22, which comprises an electrical heating member generally indicated as 23, contained within a water-tight and steam-tight envelope 24.

The said envelope 24 is closed at its lower end and has an outwardly flared flange 26 at its upper end, which fits over an annular internal shoulder 28, in an opening 25, in the upper wall of the steam header 16. Flat spring members 30 welded to the inside of the tube 12 at 32, are adapted to make contact with the lower surface of the envelope 24 to retain same in spaced relation within the water jacket and leave the lower end 75 of the envelope 24 free for expansion and contrac-

tion relative to tube 12, in both radial and axial direction, if same occurs.

The electrical heating element 23 comprises a continuous strand of resistance wire 34 of large cross section which is passed through spacer discs 36 of insulating material, to provide several vertically disposed lengths in a fixed, spaced relation, one with another.

Two halves of a sleeve or casing 38, having internal circumferential ribs 40 or the like, are placed around the discs 36, said discs being confined between the ribs 40. After assembling, the sleeve 38 may be welded at various points along the joints as indicated at 42, (see Figs. 4, 5, 6 and 7) and two rings 44—44 are placed around the sleeve at the top and welded thereto, leaving a space between, to accommodate a split insulating collar 46. Since the two halves of the casing 38 are slightly separated, as indicated in Figs. 6 and 7, open spaces will be left between, through which radiated heat can flow from the resistor 34 to the inner surface of the envelope 24; thence by conduction the heat will pass to the water or steam on the other side of such wall. Other openings may be provided in the casing 38 if desired. 100

Within the lower end of the envelope 24 is a centering block 48 of insulating material, having a recessed portion 50 adapted to receive the lower end of the casing 38, and to maintain same in a fixed spaced relation to the envelope 24. A space is left between the bottom of the casing 38 and the recess 50 to allow for longitudinal expansion of the said casing relative to envelope 24.

To assemble an entire heating unit an envelope 24 is inserted into a tube or jacket 12 through one of the openings 25 in the upper wall of the steam header 16. The flange 26 around the open, upper end of such envelope 24 is seated against suitable packing 27, resting on shoulder 28. A screw threaded collar 52, having an internal recess 54, is screwed into an internally threaded upper portion 56 of each opening 25, the lower surface of said collar being brought into clamping engagement with the flange 26, on the shell or envelope 24. A portion of said screw threaded collar 52 projects above the top of the steam header 16.

After the electrical resistance unit is assembled within the casing 38 as previously described, two halves of the split insulating collar 46 are placed around the upper portion of the sleeve 38, between the rings 44—44 and the whole is then inserted in the shell 24. The lower end of the casing 38 is placed in the recess 50, within the insulating block 48, and the split collar 46 is fitted into the recess 54, in the threaded collar 52. The top of the said collar 46 projects slightly above the top of the threaded collar 52. To retain this assembly within the envelope 24 an internally threaded annular cap 60 is screwed onto the projecting portion of the threaded collar, said cap being provided with an inwardly extending flange 62, which is adapted to be brought into contact with the upper surface of the projecting portion of the split insulating collar 46.

The annular threaded collar 52 and its contained insulating filler elements, the split ring 54 and upper disk 36, together form a removable closure for the open end of the envelope 24, and serve as means of supporting that end of the electrical heating assembly including resistor 34, spacing disks 36 and casing 38.

Terminals 61 are provided for the ends of the resistance wire 34 which comprise internally threaded lugs 63, adapted to be screwed or welded on the threaded ends of the resistance

wire 34, said lugs having threaded shanks 65 which project up through an insulating cap 67 resting on the upper ring 44. Straps or any other form of connection 71, may be used to connect 5 the units together, the straps being placed over the ends of shanks 65 and secured thereon by nuts 73.

It will be observed from the foregoing description of the standardized heating unit that an 10 interchangeable unit has been developed which can be inserted in any boiler constructed according to this invention, or can be transferred from one to another portion of any such boiler. It will also be observed that the electrical heating 15 assembly of resistor, resistor supports and the closure carrying these elements, forms a standardized unit which can be used with any envelope 24.

Each steam header, connected water header 20 and set of tubes with heating units therein contained, constitute a complete boiler section which can be used by itself when equipped with the proper feed water and steam pipe connection; or any desired number of such boiler sections can 25 be hooked up together to give the required steam producing capacity, as indicated in Fig. 3.

With the form of structure disclosed, it is also possible to control the generation of steam, by means of electrical switches 90 as shown in the 30 wiring diagram connected to the terminals 61 of one row of heating elements. Said switches 90 are so arranged that one or a group of heating elements may be cut in or out of the electrical circuit thereby controlling the volume of steam 35 output according to the requirements. Automatic control through a thermostat 92 may be had if desired. The thermostat at 92, or the switch shown in shunt therewith, cuts out an entire header section of cells all at once. The 40 switches 90 are only shown in connection with one row of steam generator tube heating elements, but it is to be understood that all of the elements are to be similarly connected. It is therefore possible to operate the necessary number 45 of cell units at full power and maximum efficiency, while cutting out the rest, instead of introducing current consuming resistances to reduce steam generation.

For these, among other reasons, it is obvious 50 that my invention discloses a construction of great flexibility for adaptation to different requirements as to output, and installation space available, with a uniform low cost of manufacture (resulting from mass production of standardized units) uniform high efficiency and low cost of replacement and repairs.

In addition to the foregoing form of structure I provide a novel form of water supply piping and steam outlet piping, which are shown in 55 Figs. 1, 2 and 3.

Regarding the water inlet, I provide a substantially U-shaped supply tube 64, each branch or arm of which has a number of downwardly disposed branch tubes 66 projecting therefrom, 60 the ends of which may be formed integrally with water header plates 68. The header plates 68 are secured to the opposite sides of the header 20 in positions which place the inlet opening 69, of each branch tube 66, below and in alignment with 65 the end member of each transverse row of water jackets 12. The main water supply inlet pipe 70 is joined at 72 to the middle of the bend in the U-shaped tube 64.

The steam outlet member also comprises a substantially U-shaped tube 74 having downwardly

disposed branch tubes 76, spaced along either branch of the U and preferably having their ends formed integrally with a steam header plate 78. Said header plates are secured to the ends of the steam headers 16, (as shown in Fig. 3) in positions which place the outlet openings 79 of the branch tubes 76, in alignment with the centers of the transverse rows of tubular water jackets 12. A main steam discharge pipe 80, is joined at 82 to the flanged end of the branch 84 at the middle of the bend in the U-shaped tube 74 and a safety valve 86 is mounted on said tube 74 adjacent the branch 84.

By this novel means of water connection an even distribution of water is supplied to the jackets and proper circulation within said jackets is assured, also, the generated steam is permitted to pass off rapidly through each of the individual branch outlets leading into the main steam outlet.

At the bottom of the water header 20, I provide a supporting base, which as here shown, comprises two angle iron members 88, secured to the bottom headers 20 of the water headers 20 as shown in Figs. 1 and 2.

To maintain a constant water level within the 100 water jackets 12, a boiler feed water pump 90 is provided in combination with a conventional form of feed water regulator indicated at 92, and a pressure controlled, automatic regulator valve 94. See Fig. 2. As this attachment forms no 105 part of my invention and is in common use I will not describe its construction and operation further than to say that variations in water level in cylinder 92 produces the proper opening or closing movement of steam throttle valve 96, which 110 will in turn stop, start, accelerate or slow down the operation of feed water pump 90, so as to prevent large fluctuations of water level in the boiler beyond predetermined limits.

It is to be understood that the usual insulating material will be supplied to cover the structure after it is assembled and that various changes can be made in the details of construction here shown and described, as forming one embodiment of my invention, any such modifications still being 120 within the scope of the invention here claimed if the principles of operation and results above explained are substantially preserved.

Having described my invention, I claim:

1. In an electrically heated steam generator, 125 an outer cellular structure comprising a plurality of vertically disposed tubes open at both ends and arranged side by side, each such tube constituting the envelope of a separate steam generating cell, electrical heating means within 130 each cell of said structure, header members joining said cells in multiples, a system of water inlet and steam outlet piping adapted to be connected to all of said headers and means for controlling the generation of steam within each cell; where- 135 by a multiple unit steam generator results, in which as many cells as necessary can be operated at maximum efficiency, while the remaining ones can be cut out and thereafter will consume no current at all.

2. In an electrically heated steam generator, 140 an outer cellular structure comprising a plurality of vertically disposed tubes open at both ends and arranged side by side, each such tube constituting the envelope of a separate steam generating cell, each cell comprising a water tube, an electrical heating element within each tube adapting each tube to perform as an independent steam generator, water and steam header members 145 adapted to join said tubes in multiples, a system 150

of water inlet and steam outlet piping adapted to be connected to all of said headers, and current controlling apparatus operatively connected to the heating elements in each tube, whereby the 5 generation of steam within one tube or group of tubes may be started or stopped as desired.

3. In an electrically heated steam generator an outer cellular structure comprising a plurality of vertically disposed tubes open at both 10 ends and arranged side by side, each such tube constituting the envelope of a separate steam generating cell, said cells being grouped in a plurality of separate but interconnected sections, each section comprising a plurality of such vertically disposed tubes, an electrical heating means within each tube, water and steam headers joined to said tubes, a system of piping joined to all the water headers and another system of piping joined to all the steam headers.

20 4. A multiple-unit, electrically heated, steam boiler comprising, in combination, a plurality of steam headers of uniform construction supported over an equal number of similarly arranged water headers, each pair of headers being connected together by a row of vertically arranged water tubes and each steam header having an opening in its upper wall registering with a water tube opening beneath, a system of piping adapted to be connected to all of said steam headers for dis- 25 charging steam therefrom and another system of piping adapted to be connected to all said water headers for delivering feed water thereto; together with a plurality of standardized electrical heating units each contained in a water tight 30 envelope open at one end, which envelope is adapted to be inserted through any one of said steam header openings with its closed end projecting into the water tube registering therewith, and means for releasably securing the other end 35 of each of said envelopes to the upper wall of said steam header and forming a steam-tight joint between the two.

5. A combination such as defined in claim 4 in which each of said systems of piping comprises 45 a U-shaped conduit having a branch at its curved portion and a plurality of inwardly extending branches along each arm of the U adapted to be connected to the header ends.

6. A combination such as defined in claim 4 50 in which the interior of each water tube is provided with yielding, inwardly extending projections between which the closed end of a heater envelope may be inserted to center the same in said tube interior, while permitting both radial 55 and axial expansion or contraction therein.

7. A combination such as defined in claim 4 in which the joint-forming means between one 60 end of said heater envelope and said steam

header comprises an annular shoulder in said header opening, an outwardly flanged lip on said envelope and an annular nut threaded into said header opening and bearing on said flanged lip, in which annular nut said heating unit is 80 supported.

8. In an electrically heated boiler the combination of an elongated steam header having a series of openings in its upper wall and a series of openings of slightly larger diameter in its 85 lower wall, each such lower opening being co-axial with one of the upper openings, a plurality of water tubes flanged into and projecting from said lower openings, a plurality of heater envelopes each having an open outwardly flanged 90 and adapted to be seated in any one of said upper wall openings, and screw threaded means for forcing said flanges against their seats to form steam-tight joints.

9. A structure such as defined in claim 8 combined with a resistor adapted to be inserted in said envelope while supported by said screw threaded means, and electrically insulating means forming said resistor support.

10. In an electrically heated steam generator 100 the combination of a plurality of sectional steam headers and water headers joined together in pairs by vertically arranged water jackets, a water tight envelope open at the upper end adapted to be inserted within any of the said 105 water jackets, an electric heating unit adapted to be supported in said envelope and means for releasably securing the open end of said envelope to the upper wall of the steam header and for forming a steam tight joint between the two. 110

11. A combination such as defined in claim 10 in which the interior of each water jacket is provided with means to frictionally engage the sides of the lower end of said envelope; whereby said envelope may be permitted to expand and 115 contract longitudinally independently of said water jacket.

12. A combination such as defined in claim 3, in which each such section has its separate pair of headers.

13. A combination such as defined in claim 3 in which each such section has its separate pair of headers, each connected at both ends to its cooperating system of piping.

14. An apparatus such as defined in claim 3 125 combined with a current supply circuit to which the said electrical heating means are connected in multiple, a switch for controlling the flow of current to each cell heater, and a group circuit breaker for simultaneously controlling such flow 130 of current to all the cells in any one section.
